UNITED STATES PATENT OFFICE.

MELCHIOR ZWICKY, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

LOOP-REGULATING MECHANISM FOR FULL-FASHIONED KNITTING MACHINES.

Application filed July 21, 1923. Serial No. 652,964.

My invention relates to full fashioned knitting machines, and particularly to improved loop-regulating mechanism therefor as fully set forth in connection with the accompanying drawings, and the novel features of which are clearly defined in the subjoined claims.

Fig. 1 is a cross-sectional view of a full fashioned knitting machine having my invention applied thereto in preferred manner; the well known machine mechanisms employed being sufficiently indicated to make clear the cooperative arrangement, and the cross-section shown being on the line 15 1—1 of Figs. 2 and 3.

Fig. 2 is a view looking in the direction of arrow 2 Fig. 1, showing the particular attached mechanism employed to carry out my invention; and Fig. 3 is a corresponding 20 plan view thereof on the line 3—3 of Fig. 2.

Fig. 4 is a partial front elevation of an end portion of the machine indicating one of the usual end narrowing screws and a special yarn-stop screw and carrier rods, 25 with selective connections to my improved loop-regulating mechanism.

The drawing indicates well known needle-bar presser mechanism in connection with which my present invention is illustrated as 30 providing a supplemental operating means adapted to independently effect loop-regulating adjustments for lengthening the loops where a reenforcing or plating thread is used; such adjustments being effected 35 from a longitudinally reciprocated member of the usual yarn-control mechanism, without interfering with the loop-regulating movements ordinarily imparted thereto from the cam shaft.

40 The known needle-bar presser mechanism indicated comprises loop-regulating shaft 10, to which known cam-determined turning movements are imparted from the cam shaft 11 (as shown for instance in my prior Patent No. 1,417,289, May 23, 1922) and transmitted to the pivotally carried needle-bar 12, through presser lever 13 and connection 14; such known movements being used, as is the supplemental movement provided for by 45 my present invention, for varidly positioning the needle-bar relative to the sinkers, so as to correspondingly vary the lengths of the loops formed in the yarn laid by the carriers. Such incompletely illustrated mech-

anism is commonly used in "Cotton" machines (Pat. No. 59,892); as is also yarn-control mechanism comprising the indicated longitudinally reciprocated slide box 17 with its friction-box rod 18, operated as usual by the Coulier shaft lever 19 to actuate the yarn-carrier rods and the loop-forming sinkers; and the carrier-rod stop mechanism for controlling the actual yarn travel during ordinary and narrowing knitting. The present invention merely provides in 65 connection with these commonly used mechanisms, additional loop-regulating means as hereinafter fully described.

In the construction indicated the cam shaft 11 is employed as heretofore to control positionings of the needle-bar 12 by means of selectively operating cams thereon, not illustrated; my present invention being adapted to effect additional positionings for slightly increasing the lengths of determined 75 loops which receive an extra yarn, as for instance in forming a determined heel high-splice or a selvage reenforcement.

As illustrated the laying of an extra 80 thread to determined needles only is commonly controlled in well known manner by either the usual narrowing screw nut 65 or special stop nuts 70—71 indicated in Fig. 4, which nuts act to determinedly stop the 85 yarn-carrying rods. Such nuts are also utilized in my improved mechanism to correspondingly control the additional loop-lengthening action which is derived from the longitudinally reciprocated member 17 through my supplemental loop-regulating 90 mechanism.

This supplemental mechanism for utilizing the reciprocating movement of the member 17, comprises, as shown, a supplementary presser-frame 25 carried by a longitudinal 95 pivot shaft 26 mounted in main-frame brackets 27, 27 and provided with a rigid top presser-bar 28, and with a depending portion 30 to which a presser-arm 31 is pivotally connected by means of a knuckle-piece 32; the rigid presser-bar 28 being determinedly 100 operated by said reciprocating member 17 as hereinafter described, so as to impart a rocking-movement to the presser-frame 25; which rocking movement is determinedly 105 transmitted to the needle bar 12 by the old regulating shaft 10 and presser lever 13 through my interposed mechanism shown.

The reciprocating slide-box member 17 which I utilize to impart the desired special rocking movements to needle bar 12, is provided with a pivotally carried depending 5 wedge-piece 35, the outer face of which is arranged to slidably bear against the vertical wall 28^a of the longitudinal presser-bar 28 as shown most clearly in Fig. 1; and this wedge-piece 35 is pressed outward so 10 as to slightly rock the presser-bar 28 as the inner face of the reciprocating wedge-piece 35 is brought into contact with coacting wedge blocks 37, 37 mounted upon a guide bar 38 fixedly supported by center-bed 15 brackets 39, 39. These wedge blocks 37, 37 are automatically adjusted upon the guide bar 38 as described in connection with Fig. 4, and the rocking movement of the bar 28 is transmitted to the loop-regulating shaft 20 10 and needle bar 12, through a connected arm 31.

The wedge-block devices 37, 37 are secured to separate extension rods 40, 40 which are respectively attachable to the oppositely 25 moving nuts of the yarn-stop screws—as indicated in Fig. 4 and hereinafter further described—so as to be automatically positioned relatively upon their guide bar 38 in accord with the positions of the connected 30 nuts and the yarn-feed fingers controlled by the latter. In connection with the adjustable devices 37, 37 an extension portion 37^a is provided between them so as to be moved to and fro ahead of the depending wedge 35 piece 35 of reciprocating member 17. This extension device 37^a is employed to insure proper cooperation with the usual sinker-operating slur-cock which is reciprocated with member 17; its length corresponding 40 with that of the straight-face part of the slur-cock, and its movement on the guide bar 38 adding such length successively to the respective devices 37, 37 as will be understood to be practically required because 45 of the reverse movements of the slur-cock.

The pivoted presser-arm 31 of presser-frame 25 is provided at its forward end with an adjustable contact point 31^a for engaging the opposed face of a contact stud 46 in the regulating-shaft arm 47, to thereby impart a turning movement to said shaft when the presser-frame is rocked by the reciprocating member 17; and said arm 31 has a projection 31^b which rides upon the periphery of 50 a special cam 48 on the cam shaft 11 so as to hold the point 31^a in raised position above the contact stud 46 excepting when cam depression 48^a permits of its being turned to operative position by spring 50. During the 55 inoperative positioning of the point 31^a the ordinary turning movements may be freely imparted to the loop-regulating shaft 10 from cam shaft 11 (by usual cams not shown); and my special mechanism for imparting additional turning movements 60

thereto from reciprocating member 17 through the pivotally carried member 28 acts only when contact point 31^a is lowered by cam 48 as stated. To provide that this lowering movement may freely occur the 70 arm 31 is preliminarily moved longitudinally by a cam projection 60 on shaft 11; said projection engaging an anti-friction roller 61 adjustably fixed to said arm 31.

The lengthening of the particular loops 75 through which an extra yarn is to be drawn, is effected by correspondingly moving the needle bar 12 rearward for the periods only during which said yarn is being carried to and formed by the determined needles and sinkers; so that it is necessary in utilizing the uniformly reciprocated member 17 to properly effect such periodic movements of the needle bar, to make its movements effective upon the presser-frame 25 only during corresponding periods of each reciprocation; and where the periods are required to vary in different courses, either in correspondence with the narrowing of the fabric as in the knitting of a reenforced selvage 90 edge or in desiredly shaping a reenforcement or plating, it is practically essential that the spacing of the devices 37—37 which effect the lengthening of the loops, be automatically varied accordingly through the connecting rods 40, 40.

In Fig. 4 I have diagrammatically indicated these devices 37—37, in connection with two different ways of automatically 100 adjusting the same through their connecting rods 40, 40. To effect their automatic spacing in accord with the narrowing of the fabric, one device 37 has its rod 40 operatively connected to the usual stop nut 65 on screw 66, while the other is similarly connected to a stop nut at the opposite end of the machine (not shown). If it is desired to effect an automatic adjustment of the loop-regulating devices 37—37 irrespective 105 of the narrowing of the fabric, these devices are connected to independent operating means; as indicated by the reversely traversed nuts 70—71 on the intermittently rotated screw 72; each of these nuts being operatively attachable, (as through rods 80, 110 81), to the respective devices 37, 37 instead of connecting the latter to the stop nuts 65, as previously set forth. The reversely traversed nuts 70, 71 also control the travel 115 of the extra yarn-carrier rods 73, 74 in well known manner, and either these nuts, or the stop nuts 65 may be selectively used by tightening or loosening the set screws 82, 82 to automatically adjust the devices 37 in 120 accord with the yarn feed.

My invention thus provides for controlling the loop lengths directly from the reciprocating yarn-feed mechanism and in accord with the laying of the yarn, irrespective of 125 the operations effected from the cam shaft 130

11. The mechanism specifically set forth may be readily modified within the scope of the invention as defined in the claims.

What I claim is:

1. In a full-fashioned knitting machine, the combination with yarn-control mechanism comprising a longitudinally reciprocated member, needle-bar presser mechanism and a rotary cam shaft operative upon the latter; of supplemental operating means for said presser mechanism actuated by said reciprocative member, and a cam on said shaft adapted to determinedly make said supplemental operating means ineffective.
2. In a full-fashioned knitting machine having a rotary cam shaft, yarn-carrier mechanism comprising a longitudinally reciprocated yarn control member, and a needle-bar presser mechanism operative by said cam shaft; supplemental needle-bar presser mechanism operated by said reciprocated yarn-control member.
3. In a full-fashioned knitting machine having a rotary cam shaft, yarn-carrier mechanism comprising a longitudinally reciprocated yarn control member, and a needle-bar presser mechanism operative by said cam shaft; supplemental operating means for said presser mechanism actuated by said reciprocated yarn-control member.
4. In a full-fashioned knitting machine having a rotary cam shaft, yarn-carrier mechanism comprising a longitudinally reciprocated yarn control member, and a needle-bar presser mechanism operative by

said cam shaft; supplemental operating means for said presser mechanism actuated by said reciprocated yarn-control member, and cam-shaft means for rendering said supplemental means operative or inoperative.

5. In a full-fashioned knitting machine comprising a needle-bar and presser mechanism therefor, yarn-carrier rods and stop nuts therefor, and a longitudinally reciprocated yarn-control member; a supplemental presser member operated by said reciprocated member, and devices movable with said stop nuts to vary the operation of said supplemental presser member.

6. In a full-fashioned knitting machine comprising a needle-bar and presser mechanism therefor, extra yarn-carrier rods with special stop-nuts therefor, and a longitudinally reciprocated yarn-control member; a supplemental presser member operative by said reciprocated yarn control member, and movable devices for varying such operation connected to said special stop nuts.

7. In a full-fashioned knitting machine, the combination with yarn-control mechanism comprising stop nuts and a longitudinally reciprocated member; of loop-regulating mechanism comprising a needle-bar presser member operated by said reciprocated yarn-control member, and devices movable with said stop nuts to determinedly vary said operation.

In testimony whereof I affix my signature.
MELCHIOR ZWICKY.
